UNITED STATES PATENT OFFICE.

HENRIE D. STONE, OF BOSTON, MASSACHUSETTS.

BOOT AND SHOE EDGE BURNISHING MACHINE.

SPECIFICATION forming part of Letters Patent No. 223,772, dated January 20, 1880.

Application filed October 13, 1879.

To all whom it may concern:

Be it known that I, HENRIE D. STONE, of Boston, in the county of Suffolk and State of Massachusetts, have invented certain Improvements in Boot and Shoe Edge Burnishing Machines, of which the following is a specification.

This invention relates to that class of boot and shoe edge burnishing machines in which a reciprocating burnishing-tool is employed and the boot or shoe is held in the hands of the operator and pressed against the burnishing-tool.

The invention has for its object, first, to enable the boot or shoe to be more easily held by the operator than heretofore when the burnishing-tool is operating on the abrupt curves of the toe and causing the boot or shoe to jump away from the tool, rendering it difficult to keep the boot or shoe in place; secondly, to enable the same tool to be employed, if desired, for burnishing the edge of the shank and the edge of the sole; thirdly, to provide improved means for supporting and permitting the partial rotation of the burnishing-tool on an axis at right angles to its operating face and for holding the tool with a laterally-yielding pressure in its normal position.

To these ends the invention consists in the improvements which I will now proceed to describe and claim.

Of the accompanying drawings, forming a part of this specification, Figure 1 represents a front view of a machine embodying my improvements. Fig. 2 represents a vertical section of the same on line *x x*, Fig. 1. Fig. 3 represents a horizontal section of the same on line *y y*, Fig. 1. Fig. 4 represents a perspective view of the tool-holder removed from the machine.

Similar letters of reference indicate like parts in all the figures.

In the drawings, A represents a suitable fixed frame supporting the working parts, hereinafter described. Said frame is provided with suitable guides B B to hold and permit the reciprocating motion of a cross-head, C, and a shaft, D, rotated by suitable means at a high rate of speed, and provided on its end with a cam or eccentric, E, which reciprocates the cross-head. F represents a tool-holder, which is connected by a hinge-joint to the cross-head

C, so as to be capable of swinging or partially rotating horizontally. Said hinge-joint is preferably composed of perforated lugs I I and J, formed on the tool-holder and cross-head, and a pin or pivot, K, passing through said lugs, as shown in Fig. 2.

The cross-head C is provided with vertical guides or flanges L L, the inner surfaces of which are segments of a circle whose center is 60 the pivot K. The tool-holder is so formed that its edges M M will fit somewhat snugly against the segmental guides L L, so that said edges will always be uniformly supported by the guides, as shown in full and dotted lines in 65 Fig. 3.

N N represent spiral springs interposed between the tool-holder and cross-head, one on each side of the hinge-joint. These springs permit the free swinging motion of the tool-holder and keep the same in a normal position when it is not turned by the pressure of the article being burnished. The lower portion of the tool-holder is cut away to form a seat, O, for the tool-shank P and two shoulders, R 75 R, to bear against the edges of said shank and support it horizontally. The shank P is curved at its upper portion, so that the burnishing-tool P' at its lower end is substantially in line with the hinge-joint connecting the tool-holder 80 and the cross-head. The shank P is detachably connected to the tool-holder by a set-screw, S, or other suitable means. The tool P' is of any suitable form and material, and it is preferably provided with a slight lip, a, sufficiently 85 wide to burnish a very narrow strip on the bottom of the sole without affording any considerable bearing for the same. The tool P' is also preferably formed with a face, b, for burnishing the edge and bottom of the shanks of 90 shoes, &c.

T represents an adjustable gage or bearing, which is supported by the frame A, and is located in such relation to the tool P' that it forms a stationary rest or bearing for the bottom of the sole of a boot or shoe while the edge thereof is being burnished by the tool. The gage T is formed on a square shank, U, which slides in a square orifice in the frame A and terminates in a threaded bolt, V. A nut, W, 100 is located on the bolt V, and is prevented from moving longitudinally thereon by suitable

stops X X, so that the rotation of said nut causes the bolt V, shank U, and gage T to move in or out to change the position of the gage with reference to the tool.

5 Operation: The cross-head being reciprocated at the rate of, say five thousand or six thousand strokes per minute, the operator takes a boot or shoe, places the bottom of the sole against the gage T, which is properly adjusted, 10 and subjects the edge to the tool P', moving the sole along over the gage as the work progresses. When the tool reaches the toe portion it has a tendency to shake or throw off the boot or shoe. To overcome this tendency the operator presses the sole firmly against the gage T, and the friction thus produced enables him to keep the boot or shoe under control, so that the toe can be burnished with much less difficulty than heretofore. The gage also enables the beveled shank-edge to be burnished by the same tool that burnishes the sole-edge, the bottom of the shank being supported by the gage, while the beveled edge of the shank is held against the burnishing-tool, as shown 25 in dotted lines in Fig. 2. The means described for connecting the shank P to the tool-holder enable the tool to be securely attached and supported and readily applied and removed. The segmental guides of the cross-head afford 30 firm bearings for the edges of the tool-holder, whatever may be the position of the latter,

and the springs keep the tool in a normal position, so that the operator is not obliged to adjust it at the commencement of the operation.

I claim—

1. In an edge-burnishing machine, the gage or rest T, having a screw-threaded shank and a thumb-nut thereon, adapted to be adjusted substantially as and for the purpose described.

2. As a means for supporting and reciprocating a burnishing-tool, the sliding cross-head C, having the segmental guides or flanges, and the tool-holder hinged to the cross-head and adapted to partially rotate and bear against 40 said guides.

3. The cross-head provided with the curved guides or flanges, in combination with a vertical centrally-pivoted tool-holder made laterally adjustable by means of supporting-springs, substantially as shown and described.

4. The tool-holder F, having the recess O and shoulders R, adapted to receive the shank of a burnishing-tool, substantially as shown and described.

In testimony whereof I have signed my name to this specification in the presence of two subscribing witnesses this 9th day of October, 1879.

HENRIE D. STONE.
